UNITED STATES PATENT OFFICE.

NATHAN SMITH, OF ELIZABETH, NEW JERSEY, ASSIGNOR OF ONE-HALF TO
JOHN F. KENAH, OF SAME PLACE.

DESIGN FOR A SUPPORT FOR HAMMOCKS.

SPECIFICATION forming part of Design No. 34,791, dated July 16, 1901.

Application filed June 4, 1901. Serial No. 63,167. Term of patent 7 years.

To all whom it may concern:

Be it known that I, NATHAN SMITH, a citizen of the United States, residing at Elizabeth, in the county of Union and State of New Jersey, have invented and produced a certain new and original Design for Supports for Hammocks, of which the following is a full and complete specification, such as will enable those skilled in the art to which it appertains to make and use the same.

In the accompanying drawing, forming part of this specification, in which like letters of reference designate corresponding parts, the figure is a perspective view of my newly-invented design for a support for hammocks, &c.

My design in its essential features consists in an ornamental circumferential base portion A, supporting a truncated rectangular pyramidal top portion a. Secured to the pyramidal

top portion a and extending upward and outward therefrom and then inward and upward in graceful curves are two oppositely-situated standards B, at the top of which is located a link C, secured to an eye-ring D, secured to the standard immediately below the top.

Having thus fully described my invention, what I claim as new, and desire to secure by Letters Patent, is—

The design for a support for hammocks, as herein shown and described.

In testimony that I claim the foregoing as my invention I have signed my name, in presence of the subscribing witnesses, this 29th day of May, 1901.

NATHAN SMITH.
